(57) **CLAIM**

An ornamental design for a anastasia thumblatch, substantially as shown and described herein.

DESCRIPTION

FIG. 1 is a perspective view of the anastasia thumblatch; FIG. 2 is a front view thereof;

FIG. 3 is a left side view thereof;

FIG. 4 is a right side view thereof;

FIG. 5 is a top side view thereof; and,

FIG. 6 is a bottom view thereof.

The broken line in FIGS. 3,4,5, and 6 is for illustrative purposes only and forms no part of the claimed design.
